CONTROL MECHANISM FOR BELT MANLIFTS

Harry Deverell, Millburn, N. J.

Application May 16, 1957, Serial No. 659,603

1 Claim. (Cl. 187—44)

This invention relates in general to so called belt manlifts that comprise an endless belt mounted on pulleys on a vertical frame that usually extends through openings in a plurality of floors in a building with the reaches of the belt vertically disposed and having connected thereto steps upon any one of which a man may step from one floor and be conveyed to another floor to which the man may step off the step.

Manlifts or elevators of this type have been known for many years and have generally included an electric motor for driving the belt, a main switch operated by an endless control rope mounted on pulleys on the frame and having one reach extending alongside each reach of the manlift belt so that a man on a step may exert a pull on the rope to actuate the switch. Also, two or three limit switches are usually included in circuit with the main switch and the motor for automatically stopping the motor in case a man fails to leave the step at the proper time at the upper end and lower end of the frame, thereby to prevent injury to the man. However, the main switch does not exclusively control the starting of the motor, because when one of said limit switches is operated to stop the motor, the motor will resume operation when the man resets the limit switch. Consequently, if another man was on the manlift he might be caused to fall by the sudden starting of the motor and the belt.

A prime object of the present invention is to provide a control mechanism which shall embody novel and improved features of construction to overcome this difficulty with the known types of manlifts and to make it impossible to start the motor except by operation of the main switch. In other words the invention contemplates a control mechanism wherein the starting of the motor shall be controlled exclusively by the main switch which in turn shall be actuated by a novel and improved actuating mechanism including a control rope for each reach of the manlift belt and novel means for transmitting motion from the control ropes to the switch.

Another object of the invention is to provide such a control mechanism wherein the means for transmitting motion to the main switch shall automatically return to a neutral position after each operation of the switch so that even if a limit switch is actuated and then reset, the belt can not be started until the appropriate control rope has been pulled in the right direction.

Other objects, advantages and results of the invention will be brought out by the following description in conjunction with the accompanying drawings in which:

Figure 1 is a fragmentary side elevation of the upper portion of a belt manlift having a control mechanism embodying the invention and showing the manlift associated with several floors of a building with portions broken away;

Figure 2 is a similar view of the lower portion of the manlift and control mechanism;

Figure 3 is a fragmentary front elevation of the upper portion of the manlift shown in Figure 1;

2

Figure 4 is an enlarged fragmentary horizontal sectional view approximately on the plane of the line 4—4 of Figure 1, showing one of the limit switches;

Figure 5 is an elevation of the portion of the elevator and the limit switch shown in Figure 4 with the switch in normal closed position;

Figure 6 is a view similar to Figure 5 showing the switch actuated into open position;

Figure 7 is an enlarged schematic composite side elevational and sectional view of the control mechanism embodying the invention; and

Figure 8 is a schematic wiring diagram of one possible electrical circuit including the main switch in accordance with the invention.

Specifically describing the illustrated embodiment of the invention, the manlift includes a vertical frame A having a base portion B that is mounted on any suitable support, such as the basement floor of a building, with the frame extending vertically through openings C in floors 20 of a building or platforms of an elevator structure. A pulley E is mounted at the lower end of the frame on a shaft 1 which is journaled in suitable bearings 2, and a similar pulley F is mounted at the upper end of the frame on a shaft 3 that is journaled in bearings 4, and a flexible wide belt G runs over said pulleys with its reaches disposed vertically. The belt is driven in known manner by an electric motor and reduction gear combination H, the output shaft of which is connected to the shaft 3 of the pulley F.

Secured to the belt in the usual manner in equidistantly spaced relation longitudinally of the belt are a plurality of steps I, each of which includes a frame 6 having two rollers 7 journaled thereon in spaced relation longitudinally of the belt at each end of the step, said rollers at the ends of the step running in corresponding vertical channel bars 8 that form parts of the frame A. Each step also has oppositely facing treads 9 so that one tread faces upwardly when the step is moving upwardly, while the other tread faces upwardly when the step is moving downwardly. A handhold 10 is secured to the belt above each step.

Above the top floor or landing and below the upper pulley F, at least one and preferably two limit switches 45 N are provided to automatically stop the belt if a person remains on the step after the step has passed said topmost floor or landing, and a similar limit switch O is provided immediately below the lowermost floor or landing D to stop the belt if a person remains on the step at said floor or landing. These limit switches are of known construction and include an actuating lever P connected to a spring biased toggle switch contact block so that the switch is normally in closed position with the operating lever P abutting a section 11 of one flange of a channel 50 bar 8 which is hinged at 12 on a bracket 13 secured to the channel bar, which hinge section 11 is normally influenced by a spring 14 into normal position in alignment with the flange of the channel bar as shown in Figure 5, a stop plate 15 on the hinge section 11 being 55 provided to limit movement of the hinge section under action of the spring. When the lower step roller 7 in the corresponding frame bar 8 engages the hinge section 11 with a person standing on the step, the belt G is slightly flexed and said roller pushes the hinge section outwardly 60 to actuate the switch into open position as shown in Figure 6 and thereby stop the motor and the movement of the belt. The switch will remain in this open position until it is manually reset.

The structure so far described is in general old and 65 no claim to novelty is made thereon. An important feature of the invention is the provision of a control mechanism including a main switch J so that the motor

can not be started after such automatic operation of said limit switches, except by manual actuation of the main switch J which is connected in circuit with the limit switches, motor starting mechanism and a brake, as hereinafter described, and the main switch can be operated only by a pull on one of the control ropes K and L.

In accordance with the invention, a lever or rocker 16 is pivotally mounted at 17 at the upper end of the frame A in closely spaced relation to one edge of the belt G and a similar lever or rocker 18 is pivotally mounted at 19 at the lower end of the frame. One control rope K has its ends adjustably connected at 20 to the corresponding ends of the upper and lower rockers, respectively, while the ends of the other control rope L are adjustably connected at 21 to the other ends of said rockers so that the control ropes are in closely spaced parallel relation to one edge of the belt G. The upper rocker 16 has at least one switch actuating arm 22 for actuating the main switch J and this operating arm is normally held in a neutral position by identical combined spring and dash pot devices M. As shown, each of these devices includes a vertically disposed cylinder 23 rigidly mounted on a bar 24 forming a part of the frame A. In the cylinder is slidably mounted a piston 25 that has a rod 26 connected to one end thereof and projecting through an opening 27 in one end of the cylinder; and said piston rod has a flexible or lost motion connection 28 with one end of the rocker. As shown, this connection is a chain, but other types of connections could be used. Preferably one end of the chain is adjustably connected at 29 to the rocker. A spring 30 interposed between the piston and one end of the cylinder, normally biases the piston toward the other end of the cylinder and exerts an upward pull on the rocker, and an air vent 31 controlled by a valve 32 is provided in the second mentioned end of the cylinder to retard the movement of the piston under the influence of the spring.

Normally the parts are so adjusted that the springs 30 will hold the rocker 16 with its arm 22 in the neutral position shown in Figures 1 and 7. Obviously a pull on either control rope K or L in either direction will swing the rocker and the arm 22 in one direction or the other, and the springs will return the rocker and its arm automatically to the neutral position. Movement of the arm 22 in one direction will actuate the main switch J to start the motor and belt, while movement of the arm in the opposite direction will stop the motor and belt.

The main switch may be of any suitable construction and there might be more than one switch. The switch will be connected in circuit with the motor, the usual magnetic contactors, magnetic starters and reverse phase relay in the usual manner. Figure 8 is a schematic wiring diagram of one possible circuit. For the purpose of simply explaining the principles of the invention, the main switch is shown as including a pair of start contact points and another pair of stop contact points. One of the start contact points 33 may be fixed in a suitable casing while the other start contact point 34 is mounted on a movable insulated carrier 35. One of the stop contact points 36 is also fixed while the other stop contact point 37 is mounted on said carrier 35. The carrier has two spaced operating fingers 38 between which is normally disposed the arm 22 of the rocker, and in normal operation, the carrier is located so that the stop contact points 36, 37 are normally closed and the start contact points 33, 34 are normally open. Assuming that a person is on a manlift step and desires to start the manlift, he will exert a pull on the adjacent pull

rope K or L in the direction opposite that in which he desires to travel and whereupon the rocker arm 22 will be swung to close the start switch and simultaneously open the stop switch, and when the pull rope is released the springs 30 will return the rocker arm to its neutral position. When the manlift belt is moving with a person on the step and it is desired to stop the belt, the adjacent control rope is simply gripped by the person and the movement of his body with the belt will exert a pull on the control rope and swing the rocker arm 22 from its neutral position in the direction to close the stop switch and open the start switch and thereby stop the belt. Then, upon release of the control rope the springs 30 will return the rocker arm 22 to its neutral position.

Preferably, all of the switch contacts will be arranged in a common housing with the operating fingers 38 projecting therefrom as shown in Figure 7.

The now preferred embodiment of the invention has been shown and described, but it will be understood by those skilled in the art that the invention may be embodied in other structural details and that different types of switches and other electrical apparatus may be utilized within the spirit and scope of the invention.

25 What I claim is:

In a belt manlift, the combination of a vertical frame having belt pulleys journaled thereon in vertically spaced relation and an endless belt carrying steps running over said pulleys and having two vertical reaches, driving means for said belt including an electrical motor and a speed-reducing driving connection between said motor and one of said pulleys, control mechanism for starting and stopping said motor including a main switch having start contact points and stop contact points and spaced apart operating fingers therefor, a control rope in closely spaced parallel relation to each reach of the belt, an actuating element movably mounted on said frame and normally disposed between said fingers in neutral spaced relation to both thereof and connected to both of said control ropes so that a pull on either control rope in the direction of movement of the corresponding belt reach will move said actuating element in one direction into engagement with one of said fingers and actuate said switch to stop said motor, while a pull on either rope in the opposite direction will move said actuating element in the other direction into engagement with the other finger and actuate the switch to start said motor, and yieldable means normally biasing said actuating element into said neutral position after each said movement of the actuating element, said control mechanism including a rocker lever pivoted intermediate its ends adjacent each of said pulleys, said control ropes being connected to the corresponding ends of said rocker levers, said actuating element comprising an arm projecting from one of said rocker levers, and the last-named means including a cylinder mounted on said frame adjacent each end of one of said levers, a piston in each cylinder having a rod extending from one end of the cylinder and flexibly connected to the corresponding end of said lever, a spring normally biasing said piston toward the other end of said cylinder, and a valve-controlled vent in the second-mentioned end of the cylinder.
